UNITED STATES PATENT OFFICE.

LAWRENCE A. FLETCHER, OF CUMBERLAND, MARYLAND, ASSIGNOR TO
NATIONAL GLASS COMPANY, OF PITTSBURG, PENNSYLVANIA, A COR-
PORATION OF PENNSYLVANIA.

DESIGN FOR A GLASS VESSEL.

No. 37,604.

Specification for Design.

Patented Oct. 31, 1905.

Application filed July 22, 1905. Serial No. 270,878. Term of patent 14 years.

To all whom it may concern:

Be it known that I, LAWRENCE A. FLETCHER, a citizen of the United States, residing at Cumberland, in the county of Allegany and State of Maryland, have invented a new, original, and ornamental Design for Glass Vessels, of which the following is a specification, reference being had to the accompanying drawings, forming part thereof.

Figure 1 is a perspective view of a glass

vessel, showing my new design; and Fig. 2 is a top plan view.

I claim—

The ornamental design for a glass vessel, as shown.

LAWRENCE A. FLETCHER.
